[57] **CLAIM**

The ornamental design for a storage device for image information storing/retrieving machine, substantially as shown and described.

DESCRIPTION

FIG. 1 is a front, top and right side perspective view of a storage device for image information storing/retrieving machine showing my new design;

FIG. 2 is a front elevational view thereof;

FIG. 3 is a rear elevational view thereof;

FIG. 4 is a right side elevational view thereof, the left side being a mirror image of the right;

FIG. 5 is a top plan view thereof; and

FIG. 6 is a bottom plan view thereof.

FIG. 1

FIG. 2

FIG. 3

FIG. 4

FIG. 5

FIG. 6
